RESTAURANT BUILDING

Thomas C. Katris, 8225 Kraay St.,
Munster, Ind. 46321

Filed Mar. 7, 1972, Ser. No. 232,647

Term of patent 14 years

Int. Cl. D25—03

U.S. Cl. D13—1 B

FIG. 4

FIG. 2

FIG. 1 is a front elevational view of a restaurant building showing my new design;

FIG. 2 is a rear elevational view thereof;

FIG. 3 is a side elevational view thereof;

FIG. 4 is a top plan view thereof taken from the right of FIG. 1, and

FIG. 5 is a sectional view taken on line 5—5 of FIG. 4.

I claim:

The ornamental design for a restaurant building, as shown and described.
